(57) **CLAIM**

The ornamental design for a housing assembly for multiple LED lights, as shown and described.

DESCRIPTION

FIG. 1 is a top perspective view of a housing assembly for multiple LED lights, showing the new design;

FIG. 2 is a bottom perspective view thereof;

FIG. 3 is a top view thereof;

FIG. 4 is a left side view thereof;

FIG. 5 is a right side view thereof;

FIG. 6 is a front view thereof;

FIG. 7 is a bottom view thereof;

FIG. 8 is a rear view thereof.

FIG. 9 is an exploded top perspective view thereof; and,

FIG. 10 is an exploded bottom perspective view thereof.

The broken lines in the drawings illustrate portions of the housing assembly for multiple led lights which form no part of the claimed design.
